UNITED STATES PATENT OFFICE.

EDWIN R. CARLSON, OF BROOKLYN, NEW YORK, ASSIGNEE OF ONE-THIRD TO MORELS KATSKY, OF BROOKLYN, NEW YORK.

RECEIVER FOR ELECTROMAGNETIC WAVES.

1,027,238.

Specification of Letters Patent. Patented May 21, 1912.

Application filed March 16, 1911. Serial No. 614,758.

To all whom it may concern:

Be it known that I, EDWIN R. CARLSON, a citizen of the United States, residing at Brooklyn, in the county of Kings and State of New York, have invented new and useful Improvements in Receivers for Electromagnetic Waves, of which the following is a specification.

This invention relates to a receiver for electromagnetic waves which is adapted to receive wireless messages from a transmitter situated at a distance.

This invention consists of devices whereby the contact point can be accurately adjusted in a vertical plane to give sensitive contact with the electrolytic fluid or mineral detecting substance.

The bracket arm of the instrument carrying the contact point can be oscillated with the base as an axis to swing the arm to any desired position and to contact with any one of a number of electrolytic substances such as silicon or a fluid such as diluted nitric acid located in the circuit of the electromagnetic waves. The contact point is adjusted by means of a spring adapted to engage the pin and operated by a screw to compress or tension the spring and thus move the pin up or down in the sleeve.

The novel features of the invention are more fully described in the following specification and claims and illustrated in the accompanying drawing in which:

Figure 1 represents a side elevation partly in section of an instrument embodying this invention. Fig. 2 is a front view of the same. Fig. 3 is a plan view of Fig. 1. Fig. 4 is a modification.

In this drawing the letter *a* designates a base which may consist of wood, hard rubber or any other well known non-conductor. To this base is fixed a stanchion *b* having a threaded bore for the insertion of and engagement of the threaded stem of a bracket *c*. A nut *d* is adapted to lock the stem of the bracket to the stanchion and thus prevent it from turning. The arm of this bracket is provided with a sleeve *e* which can be adjusted vertically along the arm to any desired position and fixed to the arm by means of a set screw *f* located at the top of the sleeve. The sleeve carries a sliding pin *g* having a notch or groove *h* formed in the stem of the pin. One end of a semi-ellip-

tical spring *i* is adapted to engage the notch 55 while the other end of the said spring is fastened to or strikes against the head of the sleeve. A thumb screw *j* has a threaded stem to engage the sleeve while the knobbed head of the screw is in contact with the face 60 of the spring. When the thumb screw *j* is actuated it will compress or tension the spring and the detector pin will slowly move up or down in the sleeve.

The base *a* is provided with a number of 65 cups *k* to contain the electrolytic fluid such as an acid, or platens *m* on which can be placed different electrolytic detectors such as silicon and peroxid of lead.

Leads *n* are fixed to binding posts on the 70 base, one of the leads being connected to the ground while the other is connected to an aerial wire not shown. This circuit can be provided with a telephone adapted to receive the vibrations created in the receiving 75 circuit as is well known. Each cup or platen is connected to the circuit and when it is desired to change from one to the other the lock nut *d* is merely loosened by turning it up off the post. In this position the 80 bracket arm carrying the pin can be swung in a circle with the stanchion bore as the axis to any of the electrolytic substances.

It will be seen that when the thumb screw 85 *j* is actuated it operates the spring to compress or tension it and hence move the pointed pin either up or down in the sleeve, this vertical movement of the pin is very slow so that sensitive adjustment of the instrument 90 is possible.

It should be said that the pin *g* is reversible, one end being brass pointed while the other end is equipped with a fine platinum wire *p* which is inserted into a split end of the pin. The wire *p* is held in place by means of a spring *o* fastened to the pin and of suitable construction to press the wire into frictional contact with the walls of the pin, thus holding the wire firmly in place. It will be understood that the platinum wire 100 can at any time be removed or adjusted when it becomes worn or useless and a new piece of wire inserted in the pin. The pin *g* may be removed from the sleeve *e* and reversed to present the platinum point of the 105 pin as indicated in Fig. 4. A pin thus designed has a double use the brass end being in operation when a substance like peroxid

of lead is used as a detector and the platinum point when an electrolytic fluid such as nitric acid is employed.

It will be obvious that the adjusting means for the contact point can be applied to a microscope and similar instruments where fine adjustment of the parts is essential.

I claim:

1. A receiver for electromagnetic waves, comprising a base provided with a plurality of electrolytic fluid and mineral substance containers, a bracket arm mounted on the base, a pin having a contact point at each end operatively carried by the arm, one end 15 of the pin being for contact with the fluid containers while the other end is adapted for use with the substances.

2. A receiver for electromagnetic waves, comprising a base provided with a plurality 20 of electrolytic fluid and mineral substance containers, a bracket arm mounted on the base, a pin having two contact points, one of the points being employed for contact with the fluid containers while the second 25 point is adapted for use with the substances.

3. A receiver for electromagnetic waves, comprising a base provided with an electrolytic container, a bracket arm mounted on

the base, a sleeve attached to the arm, a pin having a groove carried by the sleeve, a spring to engage the grooved portion of the pin, a device operatively connected to the sleeve and engaging the spring for tensioning and compressing the spring to move the pin vertically in the sleeve.

4. A receiver for electromagnetic waves, comprising a base provided with an electrolytic container, a bracket arm mounted on the base, a sleeve attached to the arm, a pin carried by the sleeve having a contact point 40 consisting of a wire inserted into a split end of the pin, and a spring secured in the split part of the pin to frictionally hold the wire in place, a spring to engage the pin, and means operatively connected to the sleeve 45 and engaging the spring for tensioning and compressing the spring to move the pin vertically in the sleeve.

In testimony whereof I have hereunto set my hand in the presence of two subscribing 50 witnesses.

EDWIN R. CARLSON.
